UNITED STATES PATENT OFFICE.

FRANZ G. HOERLEIN, OF BROOKLYN, NEW YORK.

GAS-HEATER.

SPECIFICATION forming part of Letters Patent No. 698,017, dated April 22, 1902.

Application filed August 10, 1901. Serial No. 71,562. (No model.)

To all whom it may concern:

Be it known that I, FRANZ G. HOERLEIN, a citizen of the United States, residing in New York, borough of Brooklyn, in the State of New York, have invented certain new and useful Improvements in Gas-Heaters, of which the following is a specification.

This invention relates to an improved gas-heater for the use of bakers, confectioners, and others in boiling crullers and similar articles that are finished in boiling lard, sugar, &c.

Bakers, confectioners, and others have heretofore used an ordinary kettle over a coal or wood fire, which, especially in summer, is very objectionable, as it heats up the already-warm rooms in which the bakers and confectioners work, and my improved gas-heater is designed for taking the place of the old-style heaters and substituting a gas-heater for the same; and for this purpose my invention consists of a gas-heater composed of an exterior casing provided with transverse braces, perforated gas heating-tubes, supported by said casing and the braces, air-supply openings in the side walls of the casing, and a top ring provided at its upper face with radial grooves for permitting the products of combustion to pass in outward direction.

The invention consists, further, in certain details of construction and combinations of parts, which will be fully described herein-after and finally pointed out in the claim.

In the accompanying drawings, Figure 1 is a side elevation of my improved gas-heater for bakers' and confectioners' use. Fig. 2 is a plan view of Fig. 1. Fig. 3 is a vertical longitudinal section on line 3 3, Fig. 2. Fig. 4 is also a vertical section on line 4 4, Fig. 2; and Fig. 5 is a vertical section through an interior ring adapted for use with the heater.

Similar letters of reference indicate corresponding parts.

Referring to the drawings, A represents a cylindrical casing, which is preferably made of sheet metal and provided with air-inlet openings e and at its lower part with a rim a, having an inwardly-projecting flange a'. To the inwardly-projecting flange a' are attached transverse braces B, which serve to support a number of perforated burner-tubes D, that are closed at one end and connected at the other end with a gas-supply pipe C, provided

with a main gas-cock C'. Each individual perforated heating-tube D is provided between the gas-supply pipe C and its end with an individual gas-cock C², so that the supply of gas to either one of the heating-pipes can be shut off. An adjustable register B' is arranged at the end of each gas heating-pipe adjacent to the cock C², so as to regulate the supply of air to the pipe. The ends of the arched braces B are attached to the inwardly-projecting flange a' and to the under side of the heating-pipes D, so that the latter are firmly held in position. The top part of the casing A is formed of a ring A', that is provided with a downwardly-projecting circumferential flange riveted to the casing A, and preferably made of cast metal and provided with a number of radial grooves b and intermediate raised seats b', said grooves permitting the passage of the products of combustion in outward direction when the kettle is placed in position upon the top ring. The inner circumference of the top ring A' is provided with a seat for supporting a second ring A², of smaller diameter, which is likewise provided with radial grooves and intermediate raised portions or seats, said interior ring being indicated in dotted lines in Fig. 2 and shown in cross-section in Fig. 5. This ring is provided with an interior seat for a similar smaller ring, and so on, so that the gas-heater can be used for heating large or small kettles or boilers, according to the number of crullers or other articles to be treated.

When smaller vessels are to be heated, only the central supply-pipe is employed, while the supply of gas to the outer heating-pipes is cut off. In place of the straight gas heating-pipes pipes of circular shape may be used, as I do not desire to confine myself to the special form of heating-pipes shown.

The advantages of my improved gas-heater for bakers, confectioners, &c., are, first, that the crullers or other articles can be quickly and conveniently cooked without requiring a coal fire; second, that large or small vessels can be heated with equal facility; third, that a regular and effective heating-flame is produced by the supply of air through the air-openings in the casing and the radial outlet-grooves for the products of combustion in the

top of the casing; fourth, that whenever the cooking operation is complete the gas is shut off, and thereby the heater placed out of use, so that the same does not unduly heat the 5 work-room.

Having thus described my invention, I claim as new and desire to secure by Letters Patent—

A gas-heater, consisting of a cylindrical casing provided with air-inlet openings, a rim secured to the lower edge of said casing and provided with an inwardly-projecting flange, transverse braces attached to said flange, a

burner supported on said braces, means for supplying gas to said burner, and a top ring 15 attached to the upper part of the casing and provided with radial outlet-grooves and raised seats between said grooves, substantially as set forth.

In testimony that I claim the foregoing as 20 my invention I have signed my name in presence of two subscribing witnesses.

FRANZ G. HOERLEIN.
